Attorney

UNITED STATES PATENT OFFICE.

HARRY HESS, OF SPARKS, NEVADA.

SMOKING-PIPE.

1,391,474.

Specification of Letters Patent. Patented Sept. 20, 1921.

Application filed May 18, 1920. Serial No. 382,557.

To all whom it may concern:

Be it known that HARRY HESS, a citizen of the United States, residing at Sparks, in the county of Washoe and State of Nevada, 5 has invented certain new and useful Improvements in Smoking-Pipes, of which the following is a specification, reference being had to the accompanying drawings.

This invention relates to smoking pipes 10 and particularly to a smoking pipe capable of preventing nicotine from passing through the stem of the pipe.

With the common form of smoking pipe, the stem is connected directly to the bowl of 15 the pipe and consequently the nicotine is drawn through the stem of the pipe together with the smoke.

It is therefore an object of the invention to provide a smoking pipe which eliminates 20 this disadvantage by providing means whereby the nicotine is separated from the smoke before the smoke enters the stem of the pipe.

Another object of the invention is to provide a smoking pipe of this character where- 25 in the smoke and other matter leaving the bowl of the pipe at the same time are permitted to travel a short distance before being separated, the nicotine and like matter 30 collecting in a receptacle while the smoke is permitted to pass through the stem of the pipe.

Another object is to provide a smoking pipe of this character including a bowl and a nicotine trap or receptacle disposed beneath 35 the bowl, and means connecting the bowl to the receptacle and also providing communication between the bowl and the receptacle.

Another object of the invention is to provide a smoking pipe of this character where- 40 in the bowl of a conventional form of pipe may be used without requiring alterations.

A still further object of the invention is to provide a smoking pipe of this character which does not interfere with the draft or 45 suction through the pipe.

With these and other objects in view, the invention consists in the improved construction and arrangement of parts to be herein- 50 after more particularly described, fully claimed and illustrated in the accompanying drawings, in which:

Figure 1 is a vertical elevation and sec- 55 tional view of a smoking pipe constructed in accordance with an embodiment of the in- vention, and

Fig. 2 is a horizontal sectional view of the nicotine trap or receptacle.

Referring to the drawings, 5 designates a nicotine trap or receptacle, the trap having an inlet opening 6 in one side and an outlet 60 opening 7 in the other side, said openings being aligned. The bottom of the receptacle is provided with a concavity so as to permit matter that enters the receptacle to readily collect in the bottom. 65

A tobacco receiving bowl 8 is disposed upon the receptacle 5 and is intended to be supported by said receptacle. The bowl 8 is provided with the usual outlet opening 9, said opening being disposed above the inlet 70 opening 6 of the receptacle. A conduit member 10 is provided, said conduit being preferably U-shape in formation and having its ends reduced, said reduced portions being disposed in parallel relation to each other. 75 One end of the conduit 10 is intended to be disposed in the inlet opening 6 of the receptacle. The other end is intended to be disposed in the outlet opening 9 of the bowl 8. A pipe stem 11 is provided, and has its end 80 12 reduced and threaded, said reduced portion being screwed into the outlet opening 7 of the receptacle.

In use, the smoke leaves the bowl 8 of the pipe in the usual manner and travels through 85 the conduit 10 into the trap or receptacle 5. Here the nicotine is deposited and the smoke permitted to pass out through the outlet opening 7 and pipe stem 11. In view of this novel arrangement, if desired a curved pipe 90 stem may be used in place of the straight stem. This invention also permits the use of a conventional form of bowl, as to alterations such as the formation of chambers, etc., 95 is necessary. Furthermore, the draft or suc- 100 tion of the pipe is not interfered with as the smoke is permitted to leave the pipe in the well-known manner and the nicotine is not separated upon the stem until it reaches the receptacle 5.

In view of the above, it will be readily seen that this invention provides a novel smoking pipe which provides all the desirable features of smoking, without any of the disadvantages, and these features are possessed by a device that is simple and compact. 105

What I claim is:—

1. A smoking pipe comprising a recep- 110 tacle having opposed openings in its walls,

a bowl on said receptacle, said bowl having a conventional outlet port, a conduit member having one end disposed in the outlet port of the bowl and its other end disposed 5 in one of the openings of the receptacle, and a pipe stem disposed in the remaining opening of the receptacle.

2. An attachment for a conventional form of smoking pipe comprising a receptacle 10 adapted to engage the bottom of a bowl of a

smoking pipe, a goose-neck conduit adapted to connect the bowl to the receptacle, said goose-neck being disposed exteriorly of the bowl and the receptacle, and a pipe stem carried by and communicating with the receptacle. 15

In testimony whereof I hereunto affix my signature.

HARRY HESS.
